UNITED STATES PATENT OFFICE.

ANDREW J. BELANG, OF PORT LEYDEN, NEW YORK.

TUBULAR-KNIT UNION SUIT.

Application filed August 24, 1926. Serial No. 131,227.

This invention relates to a tubular knit union suit which is specifically adapted as an undergarment for children but obviously the same features of novelty may be incorporated in similar knit garments for juniors and adults where flexibility, strength and durability are essential requisites.

In garments of this character a tubular knit section is selected of sufficient length 10 to make the body and legs in one continuous piece and is then cut to a selected pattern so that approximately the upper half may form the body and the lower half both of the legs, the body portion being slit from the upper 15 ends of the legs or thighs to the neck portion while the posterior at the junction of the body and leg portions is usually cut away for obvious purposes and replaced by a suitable gusset which forms the back flap to 20 cover the opening.

This gusset is preferably made from a separate section of the knit tube and aside from the sleeve and trimmings is the only extra part to be supplied to complete the 25 garment.

One of the objects is to cut the main tubular section and gusset section in such manner as to effect a greater saving of material, time and labor in their assembly than has 30 heretofore been practised and at the same time to increase the flexibility of the garment both longitudinally and transversely.

Another object is to obtain a more perfect fit of the garment particularly at the junction of the body and legs or around and between the thighs than has heretofore been 35 practised.

In other words, I have sought to greatly increase the output of garments of this class 40 and at the same time to reduce the cost of manufacture.

Another object is to cut the main tubular section and gusset in such manner that the gusset may substantially close the posterior 45 opening when the flap of the gusset is dropped and that the drop flap may form with the portion of the body overlying the opening a double thickness of the tubular knit material of sufficient area to allow maximum 50 expansion of the double thick portion without revealing any part of the opening.

Other objects and uses relating to specific parts of the garment will be brought out in the following description.

55 In the drawings:

Figure 1 is a face view of a tubular knit

section from which the body and legs are formed, the dotted lines indicating the outline of the pattern along which the top is 60 cut.

Figure 2 is a face view of the tubular knit section after being cut along the dotted lines indicated in Figure 1.

Figure 3 is a face view of a separate tubular knit section from which the gusset is to 65 be cut as indicated by dotted lines therein.

Figure 4 is a face view of the gusset after being cut along the dotted lines indicated in Figure 3.

Figure 5 is a rear face view of the portion 70 of the partially completed garment, partly broken away, showing the manner of securing the gusset to the posterior of the body at its junction with the legs before the lower edge thereof is stitched to the opposite edges 75 of the lower front portion of the body.

Figure 6 is a front face view of a portion 80 of the garment, partly broken away showing the gusset and upper edge of the rear opening before being stitched to the opposite edges of the front portions of the thighs.

Figure 7 is a front face view of a portion 85 of the same garment with the gusset stitched in place.

Figure 8 is a front face view of the completed garment except that the arms are 90 broken away.

Figure 9 is a rear face view of the completed garment with the arms broken away and the flap of the gusset in its open position.

As illustrated in Figure 1 the tubular section is flattened so that the folds along its opposite edges extend along the approximately longitudinal centers of the front and back of the garment to form an upper body portion —a—, an intermediate thigh portion —b— and lower leg portions —c—, all of which parts are integrally united from end to end.

The intermediate portion of the flat tube is adapted to be cut inwardly from the opposite folded edges on transverse lines —1— and —2— and also along diagonal lines —3— and —4— to form triangular recesses —5— and —6— as shown in Figure 2.

These transverse lines —1— and —2— are disposed at substantially right angles to the longitudinal center of the tube, the cutting line —1— being extended from the rear 110 folded edge the major portion of the distance from said edge to the longitudinal

center of the flat tube or more accurately a distance somewhat less than the distance between the longitudinal center of the back and the longitudinal centers of the opposite sides 5 of the body and constitutes what may be termed the lower end of the back of the body portion —a— at its junction with the thigh portion —b—.

The transverse cutting line —2— extends 10 inwardly from the longitudinal center or fold of the tube parallel with but in a plane below the cutting line —1— and may be designated as the lower end of the front of the thigh portion —b— but is considerably 15 shorter than the transverse cutting line —1— and wholly at the front side of the longitudinal centers of opposite sides of the tube for receiving the portions of the gusset hereinafter described.

20 The diagonal cutting line —3— extends from the inner ends of the transverse lines —1— downwardly and outwardly to the rear fold or longitudinal center of the back of the tube some distance below the opposite 25 transverse cutting line —2— and, therefore, diagonally across the upper rear edges of the leg portions —c—.

The opposite diagonal cutting line —4— extends from the inner end of the transverse 30 line —2— downwardly and forwardly to the longitudinal center or fold at the front at a point directly opposite and at about the same horizontal plane as the lower rear end of the diagonal line —3— and, therefore, 35 diagonally across the upper front edges of the leg portion —3—.

Briefly stated, a triangular piece is cut out of the intermediate portion of the back of the tube and a relatively smaller triangular piece is cut out of the intermediate portion of the front of the tube so that when the tube is folded along the longitudinal centers of its opposite sides an opening in the form of an isosceles or deltaic triangle 40 will be formed in the rear or posterior of the garment while a small but similar opening will be formed in the front of the garment.

The body portion —a— and thigh portion 50 —b— is adapted to be cut along a vertical line —7— at one side of and parallel with the longitudinal center or fold at the front of the tube and extending from the transverse line —2— to the lower end of the front 55 portion of the neck line —8— as shown in Figure 1 to form a front buttoning flap —9— which is of sufficient width to overlap and to button upon the opposite edge without the overdrawing or stretching of the 60 fabric.

The upper end of the tubular section is also adapted to be cut along pattern lines —8— and —8'—, 9—9 and 10—10 to form the outlines for the neck, shoulders and arm 65 holes.

The lower portion of the knit tube is also adapted to be cut along a transverse bottom line —11— and opposite lengthwise curved lines —12— and —12'—, the lines —12— extending from the rear ends of the transverse lines —11— to the lower ends of the diagonal lines —3— while the lines —12'— extend from the front ends of the transverse lines —11— to the lower ends of the diagonal lines —4—.

The tubular knit section shown in Figure 3 is adapted to be cut along lower and upper transverse lines —13— and —13'— and along longitudinally extending diagonal lines —14— and —14'—, the transverse 80 lines —13— and —13'— being extended inwardly a predetermined distance from one of the folded edges of the flat tube while the lines —14— and —14'— extend toward each other in intersecting planes so as to 85 form an obtuse angle at the intersection.

The line —13'— is preferably disposed at right angles to the fold while the line —13— is disposed at an obtuse angle to the fold between the transverse lines.

The portion of the tubular section within the lines —13— and —13'— and —14— and —14'— constitute what may be termed a combined gusset and back flap section —15— as shown in Figure 4 which, when unfolded, is of substantially the same form as shown in Figure 5.

The width of the lower edge —13— of the folded gusset is substantially equal to the length of the diagonal cut —4— plus the shorter transverse edge —2— and, therefore, the total width of the lower edge of the gusset, when unfolded, is approximately equal to the combined lengths of the diagonal cuts —4— plus the combined widths of the transverse edges —2— except as to the width of the buttoning flap —9— to permit the lower edge —13— of the gusset to be stitched along the edges —4— and —2— without distorting or excessively puckering 100 this portion of the garment.

The straight diagonal edges —14— of the combined gusset and back flap section —15—, when unfolded, is substantially equal to the corresponding diagonal edges —3— and are adapted to be stitched thereto so that when the garment is completed the entire portion of the section —15— above the intersection of the lines —14— and —14'— may extend a corresponding distance above 110 the top of the upper edge —1— of the opening —5— to form a back flap or closure adapted to overlap upon the overlying portion of the back of the garment when closed and to swing outwardly and downwardly 120 about the line —1— as an approximate axis when opened.

The total width of the section —15— at the intersection of the lines —14— and —14'— is slightly greater than the combined 130

widths of the transverse lines or edges —1— so as to create an extra transverse fullness at this portion of the garment for obvious purposes.

5 The width of the upper edge —13'— of the section —15—, when unfolded, is about the same as the lower edge —13—, both of said edges being of less width than the intermediate portion at the intersection of the 10 lines —14— and —14'— so that the lower and upper portions of the combined gusset and flap are tapered in opposite directions.

The lower tapered portion forms what may be termed the gusset proper while the 15 upper tapered portion constitutes a back flap or closure —15'— extending some distance above the upper edge of the opening —5— and forming with the adjacent back portion of the body —a— a double thickness when 20 the parts are assembled for use and the flap closed and at the same time preserving the full elasticity of this portion of the fabric in all directions.

After the sections of the garment have 25 been cut in the manner described the edges —12— and —12'— of each leg portion —c— are stitched together in any well-known manner to give the desired finish following which the combined gusset and flap section 30 —15— is placed in operative position with the intersecting points of the lines —14— and —14'— registered with the opposite ends of the line —1— as shown more clearly in Figure 5 which brings the edges —14— 35 adjacent the edges —3— whereupon the adjacent edges of both parts may be stitched together in a well-known manner leaving the flap portion —15'— free to fold along the line —1—.

40 The lower edges —13— of the gusset section —15— are then stitched to the corresponding edges —4— and —2— at opposite sides of the longitudinal center of the front side of the garment with the button flap —9'— overlapping upon the opposite edge of the front of the garment as shown in Figure 7.

This stitching of the opposite edges —14— and lower edges —13— of the gusset section 50 —15— may be continuous from end to end or practically in one operation, it being understood that the button flap —9'— and adjacent edge of the front will have been suitably reinforced and finished preceding 55 the stitching of the gusset in place.

When the upper edges —9— of corresponding shoulder portions are stitched together and properly finished the marginal edges —8— and —8'— of the neck and also 60 the lower edges —11— of the leg may be suitably finished to give these portions of the garments the desired neat and characteristic appearance following which the suitable sleeve sections —8— may be stitched to

the marginal edges —10— of the sleeve 65 openings in the garment.

The opposite sides of the body portion of the garment may be reinforced by fabric straps —16— of the same or different material stitched thereto and extending from 70 the lower edges of the arm holes to approximately the waist line.

Additional reinforcing straps —16'— extend from the waist line at the front over the shoulders and down the back to the upper edge —1— of the opening —5— at opposite sides of the longitudinal center of the garment, said straps being also stitched to the garment throughout their lengths.

An additional reinforcing strap —16''— 80 extends along the longitudinal center of the back portion of the body from the upper edge —1— of the opening —5— to the neck portion and is stitched to the body of the garment throughout its length for reinforcing purposes.

These straps are provided near the waist line at the front and back with suitable buttons —17— to which may be attached any external garment such as trousers. The button flap —9'— is provided with suitable buttonholes at intervals throughout its length for receiving buttons as —17— which are secured to the underlying portion of the front of the garment.

A garment made in accordance with the foregoing description and the accompanying drawings is particularly simple, flexible and durable and at the same time greatly reduces the time and labor incidental to its manufacture thereby reducing the cost of production and permitting a greater output for a given period of time than has been heretofore practised.

What I claim is:—

A union suit comprising a one-piece tubular-knit section of sufficient length to form a body portion, a thigh portion and leg portions, said section having deltaic openings in the front and back thereof, the rear opening being considerably larger than the front opening and having its top wall disposed at substantially right angles to its longitudinal center and its side walls converging downwardly from opposite ends of the top wall,

115 the front opening having its top wall disposed at substantially right angles to the longitudinal center of the section and its side walls converging downwardly from opposite ends thereof, the top wall of the larger opening being located at approximately the junction of the body portion and thigh portion while the top wall of the smaller opening is disposed approximately at the junction of the thigh portion and leg portions,

120 and a combined gusset and flap section having portions of its opposite longitudinal edges tapered downwardly from points in-

termediate the length thereof and stitched to the downwardly converging walls of the larger opening, the transverse width of the second-named section between said 5 points being slightly greater than the top wall of the larger opening, the width of the lower end of the gusset section being approximately equal to the combined lengths of the downwardly converging side walls

and top wall of the smaller opening and 10 stitched thereto, the portion of the gusset section above said points being unattached to the first-named section and free to fold to and from a position across the back of the body portion of said first-named section. 15

In witness whereof I have hereunto set by hand this 12th day of August, 1926.

ANDREW J. BELANG.
